UNITED STATES PATENT OFFICE.

HERBERT MIDGLEY, OF WORCESTER, MASSACHUSETTS.

SPACING-MACHINE FOR CARD-CLOTHING.

1,280,799.

Specification of Letters Patent.

Patented Oct. 8, 1918.

Application filed January 29, 1917. Serial No. 145,245.

To all whom it may concern:

Be it known that I, HERBERT MIDGLEY, a citizen of the United States, residing at Worcester, in the county of Worcester and 5 State of Massachusetts, have invented a new and useful Spacing-Machine for Card-Clothing, of which the following is a specification.

This invention relates to a machine for 10 removing sections of teeth from card clothing so as to provide clear spaces thereon.

The principal objects of the invention are to provide a simple and convenient means for removing the teeth without injuring the 15 remainder of the teeth or displacing them; and more specifically to provide means whereby a large number of these teeth can be forced back through the card clothing, then pulled out and entirely detached; 20 means for holding the card clothing during these operations and guiding it, and means for automatically releasing it from the holding means so as to permit it to be drawn through the machine.

25 Further objects and advantages of the invention will appear hereinafter.

Reference is to be had to the accompanying drawings in which—

Figure 1 is a plan of a machine constructed 30 in accordance with this invention;

Fig. 2 is a side view of the same;

Fig. 3 is an enlarged longitudinal sectional view of a portion of the machine on the line 3—3 of Fig. 1, that is, through the center of the machine;

Fig. 4 is a similar view on the line 4—4 of Fig. 1 at the discharge end of the machine;

Figs. 5, 6 and 7 are transverse sectional views on the line 5—5, 6—6 and 7—7 respectively of Fig. 1, and

Fig. 8 is an enlarged side view of the releasing device for the holding means, with parts in section and showing it in a different position from that shown in Fig. 2.

45 For certain purposes the teeth of card clothing are removed to provide clear spaces, and this is ordinarily accomplished, so far as I know, by hand, that is, an operative inserts a point under one or more of the U-shaped teeth and removes them by pulling them out from the back. This comparatively slow hand operation necessitates some care in getting the spaces accurate and introduces the possibility of error and even 50 injury to the goods. The principal object of this invention is to do away with this

hand operation and perform the same function entirely by machinery.

Referring to the drawings, the invention is shown in the form of a long frame 10 having its side walls spaced apart to form guides for the card clothing A which is placed at the left-hand end of the machine, as shown in Fig. 1 with its teeth B down. It is threaded through the machine under a 60 stationary holding plate 11 and under a vertically reciprocable holding plate 12. Under this plate 12 there is a transverse shaft 13 adapted to be operated by a handle 14 secured to one end thereof and moving between 65 stops 15 and 16 on the frame. On this shaft are two cams 17, one at each end, on which rest the ends of a support 18 for the cross plate 12. These ends 18 are held down on the cams by a pair of strong springs 19 and 70 are adapted to be raised by the operation of the cams. The plate 12 has a plurality of screw holes for receiving a fastening screw 9 by which the plate is held in adjusted positions. 80

Between the side guiding walls is an oscillating member 20 pivoted on a stud 21 and provided with a projecting portion 22 which rests on a cam 23 also on the shaft 13. On the top of this projection 22 is a removable 85 plate 24 located under the space between the two plates 11 and 12. The oscillation of the shaft 13 in addition to the operation above described also raises the plate 24 for the purpose of engaging the bottoms of the teeth 11 and 12 into the position shown in Fig. 3. On account of the bend which occurs in the legs 90 of the teeth they are forced up in this way only until these knees come to the underside 95 of the card clothing, or slightly within the surface thereof.

After the parts assume the position shown at the left-hand end of Fig. 3, the handle 14 is reversed to the position shown in Fig. 2 100 which brings up the support 18 and the plate 12 with it so that the latter clears the tops of the teeth b which project above the card clothing. Then the card clothing can be drawn along by hand through the device 105 and between adjustable top guides 25. It then passes on a platform 26 beyond the end of the member 20 and into the next part of the machine.

Here it passes between the guides with 110 the partially extracted teeth b projecting upwardly from its back and comes into the po-

sition shown at the right of Fig. 3. The left-hand guide is a stationary surface of the frame 10, but at this point an adjustable right-hand guide 27 is provided having 5 fastening devices 28 and a handle 28^a. Longitudinal ways 29 are shown between which the card clothing passes, and over these ways is located a slide 30. This is provided with a rack 31, the teeth of which project 10 downwardly, and under this is a stud 32 on which there is a gear or pinion 33 meshing with the rack for operating it. Fixed with respect to this pinion is a handle 34 which moves back against a stop 35 when out of 15 operation. This handle obviously can be oscillated to reciprocate the slide 30 forwardly along the ways 29 and back again. Under this slide 30 a plate 36 is fixed by means of a thumb-screw 37 and adjusting 20 screws 38. This plate has a projection 39 which extends up into an opening in the bottom of the slide 30. It will be seen that it can be adjusted to any desired height, and adjusted to a slight angle to the horizontal 25 if desired. This plate 36 is provided with a plurality of projecting plows 40 which are spaced apart thereon in accordance with the width of the rows of U-shaped teeth, so that one of these projects under each of the rows 30 of teeth. The reciprocation of the slide 30 of course sweeps these plows along under the rows of teeth and as the points slant backwardly they will withdraw the teeth from the card clothing. The teeth can then 35 be removed by any desired means. Although I have shown no means for removing them I have found an electromagnet a convenient device for accomplishing this result.

The operation of extracting the teeth beginning completed, the handle 34 is drawn back against the stud 35. In other words, when not operated it is always brought back to the position shown in Figs. 1 and 2. The bringing of the slide 30 back to this position has 40 another function because the end of the rack 31 engages an upwardly extending projection 41 from a wedge-shaped slide 42 which is normally pressed by a spring 43 forwardly up an inclined plane 44. This wedge-shaped 45 slide 42 has preferably a soft surface formed of a strip of leather or rubber 45 and is designed when forced upwardly by the spring into the position shown in Fig. 4 to engage the under ends of the teeth of the 50 card clothing and grip it into engagement with the top plate 47 which covers this part of the device. But when the rack moves back and engages the projection 41 the wedge-shaped slide 42 is forced back positively, and consequently the teeth released, so that the operative can pull the card 55 clothing through. The motions of the slide 24 are limited by a pin 46 which extends through a slot 47 in the side of the frame, this slot being arranged parallel with the

plane 44. The movement of the card clothing through the machine can be accomplished automatically, but is preferably accomplished by hand so no means is shown herein for doing it.

The operation of the device is very simple. The card clothing is threaded through the left-hand end of the machine under the plates 11 and 12 when the latter is in the position shown in Figs. 1 and 2, 70 and brought to the proper position, when the handle 14 is swung over to the position shown in Fig. 3. This lowers the plate 12 into the position shown in Fig. 3 and raises the plate 24 so as to force the wires up through 75 the card clothing, as shown in that figure, leaving their U-shaped portions projecting from the back. During this operation it is to be observed that the plate 12 is located down on the surface of the card clothing, 80 being held there by the springs 19. The handle 14 is then reversed back to the position shown in Figs. 1 and 2 against the stop 15 which raises this plate 12 and lowers the plate 24, and it is at this time that the operative 85 pulls it through for another space. This can be controlled by measurement or by the eye of the operative, or the plate 12 can be made just wide enough so that the upwardly projecting teeth can be brought 90 back against it to secure the proper spacing. As soon as enough of these operations have 95 been performed to bring the first projecting teeth b into the vicinity of the extracting plows 40 the handle 34 is swung forward to the dotted line position in Fig. 2, and then back to its normal position shown in full lines. This carries these plows under the teeth and extracts them entirely from the card clothing. During this operation 100 the card clothing is held against motion backwardly by the wedge-shaped plate 42 coming into the position shown in Fig. 4. The backward motion of the handle 34 then releases the card clothing, as previously described, and the operative can then pull it through. On account of pulling the material through by hand he has a chance to inspect it and exercise due care to see that 105 the machine is being operated properly, but the production is immensely increased over any method of accomplishing this result that I have known of heretofore.

Although I have illustrated and described only a single form of the invention I am 110 aware of the fact that many modifications can be made therein by any person skilled in the art without departing from the scope of the invention as expressed in the claims. Therefore I do not wish to be limited to 115 all the details of construction herein shown and described, but what I do claim is:—

1. In a spacing machine for card clothing, the combination of a guide for the card clothing, with means adapted to engage the back 120

- surface thereof, and means for engaging the points of the teeth and forcing them toward the card clothing so that their other ends project from the back thereof.
5. 2. In a machine of the character described, the combination of a frame, two plates spaced apart for engaging the back surface of a strip of card clothing, and means for engaging the ends of the teeth between said plates and forcing them outwardly from the back thereof in the space between the plates. 70
10. 3. In a machine of the character described, the combination of two plates spaced apart for engaging the back surface of a strip of card clothing, and means for engaging the ends of the teeth between said plates and forcing them into the space between said plates, one of said plates being stationary and the other movable. 75
15. 4. In a machine of the character described, the combination of a frame, a plate for engaging the back surface of a strip of card clothing, means for engaging the ends of the teeth adjacent to said plate and forcing them outwardly from the back thereof, yielding means for holding said plate down, and positive means for forcing it up to permit the card clothing to be drawn through 80
20. 30 under it with its teeth projecting from its surface. 85
5. In a spacing machine for card clothing, the combination of a frame having a guide way for receiving the card clothing, a shaft adapted to oscillate, a cam on said shaft, and means operated by said cam for forcing teeth of the card clothing through the back thereof. 90
40. 6. In a spacing machine for card clothing, the combination of a frame having a guide way for receiving the card clothing, a shaft adapted to oscillate, a cam on said shaft, and means operated by said cam for forcing teeth of the card clothing through the back thereof, another cam on said shaft, and means operated by the second cam for holding the back of the card clothing in position during the operation of the first-named cam. 95
45. 7. In a spacing machine for card clothing, the combination of means for receiving the card clothing, a shaft adapted to oscillate, a cam on said shaft, means operated by said cam for forcing teeth of the card clothing through the back thereof, another cam on said shaft, and means operated by the second cam for holding the back of the card clothing in position during the operation of the first-named cam and for releasing the same after the operation of the first cam is completed to permit the card clothing with its projecting teeth to be drawn through the machine. 100
50. 8. In a machine of the character described, the combination of a shaft having two cams thereon, a pivoted member projecting over
- one of said cams and having means for engaging the teeth of the card clothing, whereby when the cam operates said means will push the teeth inwardly, a holding plate having a projection normally engaging the second cam, and yielding means for holding it against the second cam, whereby upon the oscillation of the shaft said holding plate will be drawn down by the yielding means and then raised by the cam. 105
9. In a machine of the character described, the combination of a guide along which a strip of card clothing can be moved, means adjacent to said guide for forcing teeth of the card clothing through the back thereof, and means adjacent to the guideway for engaging said teeth and completing their extraction from the card clothing. 110
10. In a machine of the character described, the combination of a guideway along which card clothing is adapted to be moved, means adjacent to said guideway for forcing teeth out of the card clothing so as to project from the back thereof, a series of plows in position to engage the projecting teeth, and means for reciprocating said plows to cause them to withdraw the teeth from the card clothing. 115
11. In a machine for extracting teeth from card clothing, the combination of a guide for the card clothing, a reciprocating member, an adjustable plate carried thereby, and a series of plows having wedge-shaped points thereon carried by said plate and located over said guideway. 120
12. In a machine for extracting teeth from card clothing, the combination of a guide for the card clothing, a reciprocating member, an adjustable plate carried thereby, a series of plows having wedge-shaped points thereon carried by said plate and located over said guideway, and a rack and pinion construction for reciprocating said plate. 125
13. In a machine for extracting teeth from card clothing, the combination of a guide for the card clothing, a reciprocable slide plate carried thereby, a series of plows having wedge-shaped points thereon carried by said plate and located over said guideway, and means at the rear of said member for holding the card clothing against moving backward during the reciprocation of said member. 130
14. In a machine for extracting teeth from card clothing, the combination of a guide for the card clothing, a slide, a series of plows having wedge-shaped points thereon carried by said slide and located over said guideway, means for reciprocating said slide, a projection in the path of said rack, and a wedge-shaped slide movable with said projection for engaging the teeth of the card clothing and holding it against movement during the reciprocation of said slide.
15. In a machine of the character de-

21
scribed, the combination of a movable device for extracting the teeth from the card clothing, a frame on which it is supported having an inclined surface, a wedge-shaped 5 slide resting on said inclined surface, yielding means for forcing said slide up the inclined surface, said slide having a surface adapted to engage under the teeth of card clothing to hold it in position, and a projection connected with said slide for reciprocating it against the action of said yielding means to release the card clothing from it.

16. In a machine for extracting teeth from card clothing, the combination with means 10 for supporting the card clothing, of a series 15 of plows having wedge-shaped points there-

on, and means for moving said plows along the back of said card clothing, and means for guiding said plows to move in a path just beyond the back of the card clothing so 20 as to avoid the teeth in normal position in the card clothing and to engage and remove any partially extracted teeth in their path.

17. In a machine of the character described, the combination of means for forcing teeth of the card clothing through the back thereof, and means for engaging said teeth on the other side and completing their extraction from the card clothing.

18. In testimony whereof I have hereunto 25 affixed my signature.

HERBERT MIDGLEY.
